UNITED STATES PATENT OFFICE.

ERHARD GRÜBLER, OF BORSDORF, NEAR LEIPZIG, GERMANY.

RAILROAD MOTOR CAR.

Application filed April 4, 1925. Serial No. 20,800.

- My invention refers to railroad motor cars for use in town and interurban traffic, and it more particularly concerns the arrangement of an internal combustion motor on 5 cars of this type. It is an object of my invention to connect the motor with the car in such a manner that the motor can easily be inspected and repaired, without dismantling the frame or the body of the car.
- 10 In railroad motor cars driven by an internal combustion motor it has been customary to dispose the motor underneath the car in order to reserve the space available above the car bottom as far as possible for 15 the passengers and luggage. The motor either stands in a case which can be opened on all sides allowing the motor to be withdrawn in downward or upward direction, or else the motor is mounted below the car 20 bottom in horizontal position.
- While the arrangement mentioned in the first place requires a motor of very little height which opposes itself to an economical design, a motor mounted in horizontal position below the car bottom is not easily accessible unless the greater part of the bottom be arranged to be folded, this being undesirable inasmuch as it requires removal of the passenger seats.
- 25 All these drawbacks are avoided according to the present invention by arranging the motor preferably in horizontal position for horizontal displacement in a frame displaceably mounted below the car, so that by 30 displacing the frame carrying the motor and accessories all these parts can easily be inspected and repaired.
- In the drawings affixed to this specification and forming part thereof a railroad 35 motor car embodying my invention is illustrated diagrammatically by way of example, Fig. 1 being a side elevation of part of the car with the motor arranged in place below the car.
- 40 Fig. 2 is a plan view drawn to a larger scale of the motor and accessories mounted on the displaceable frame.
- Referring to the drawings, *a* is the car 45 body and *n* is the under frame carrying the body. *o* and *m* are the body queen posts and *p*, *q*, *r* are the truss rods of the truss reinforcing the underframe *n* of the car. The horizontal rods *r* carry the frame on 50 which the motor is mounted, this frame being formed by two parallel longitudinal rails *b* and four transverse rails *c* connecting them. The middle rails *c* which are preferably U-shaped in cross section rest directly on the rods *r* and can be freely displaced theron in a direction at right angles to the longitudinal car axis.
- 55 On the middle rails *c* is mounted the motor *d*. Near the side rails *c* are mounted two radiators *e* and fans *f*. *g* is the fuel tank, *h* a tool box, *i* the fly wheel and *k* is the Cardan shaft transmitting power to the driving mechanism (not shown) arranged in a casing *l*.
- The frame *b*, *c* carrying the motor and accessories is fixed in position on the rods *r* of the truss by suitable means (not shown). It can easily be shifted sideways without the Cardan shaft *k* being disengaged from the motor shaft or from the driving gear, the Cardan shaft being provided with a 75 telescoping extension as usual. The frame carrying the motor can be shifted so far that the shaft *k* contacts with the queen post *m* of the truss. In this position the motor can be inspected and repaired. The exhaust and 80 the gearing connecting the motor with the driver's stand should be designed in such a manner as to allow a lateral displacement of the motor without first disengaging these parts.
- 85 As the fuel tank, radiator and other accessories are mounted on the same frame, the motor can be started also when the frame carrying it is displaced outwards.
- If it is desired to lift the motor off the 90 car, the Cardan shaft *k* as well as the exhaust and the governing mechanism are disengaged from the motor in a suitable manner and the frame *b*, *c* carrying the motor and accessories can then be withdrawn entirely.
- 95 Obviously the frame carrying the motor, instead of being mounted for lateral displacement on the horizontal rods of the truss, might also be suspended below the 100 underframe of the car in some other suitable manner. I may for instance also mount it near one of the ends of the car in a position where it can be displaced in longitudinal direction.
- 105 I wish it to be understood that I do not desire to be limited to the exact details of construction shown and described, for obvious modifications will occur to a person skilled in the art.
- 110 I claim:
1. Railroad motor car comprising an un-

derframe, a frame arranged below said underframe for horizontal displacement relatively to said underframe and an internal combustion motor mounted on said frame.

5. Railroad motor car comprising an underframe, a frame arranged below said underframe for horizontal displacement relatively to said underframe and an internal combustion motor mounted on said frame 10 in horizontal position.

6. Railroad motor car comprising an underframe, a frame arranged below said un-

derframe for horizontal displacement relatively to said underframe and an internal combustion motor, a fuel tank and a radiator mounted on said frame.

7. Railroad motor car comprising an underframe, a truss mounted below said underframe and a frame arranged on this truss for lateral displacement, an internal combustion motor being arranged on said frame.

In testimony whereof I affix my signature.

ERHARD GRÜBLER.
